Primary Examiner — Rachel A. Voorhies*Assistant Examiner* — Benjamin D. Wannemacher(74) *Attorney, Agent, or Firm* — ScienBiziP, P.C.(57) **CLAIM**

The ornamental design for a curtain rod bracket, as shown and described.

DESCRIPTION

FIG. 1 is a right, front, and top perspective view of a curtain rod bracket, showing my design.

FIG. 2 is a left, rear, and bottom elevation view thereof.

FIG. 3 is a right elevation view thereof.

FIG. 4 is a left side elevation view thereof.

FIG. 5 is a front side elevation view thereof.

FIG. 6 is a rear plan view thereof.

FIG. 7 is a top plan view thereof.

FIG. 8 is a bottom plan view thereof; and,

FIG. 9 is a perspective view thereof in the rotatable state. The broken lines in the drawings depict portions of the curtain rod bracket that form no part of the claimed design. The dot-dot-dash lines define the bounds of the claimed design and form no part thereof.
